[57] CLAIM

The ornamental design for a tumbler or similar article,
substantially as shown and described.

DESCRIPTION

FIG. 1 is a front elevational view of a tumbler or similar
article;

FIG. 2 is a rear elevational view thereof;

FIG. 3 is a side elevational view thereof, as viewed
from the right hand side of FIG. 1;

FIG. 4 is a side elevational view thereof, as viewed
from the left hand side of FIG. 1;

FIG. 5 is a top plan view thereof;

FIG. 6 is a bottom plan view thereof;

FIG. 7 is a sectional view thereof, taken along lines 7—7
of FIG. 3, looking in the direction of the arrows;

FIG. 8 is a sectional view thereof, taken along the lines
8—8 of FIG. 3, looking in the direction of the arrows;

FIG. 9 is a sectional view thereof, taken along the lines
9—9 of FIG. 5, looking in the direction of the arrows;

FIG. 10 is a sectional view thereof, taken along the lines
10—10 of FIG. 5, looking in the direction of the arrows;

FIG. 11 is a sectional view thereof, taken along the lines
11—11 of FIG. 5, looking in the direction of the arrows;

and

FIG. 12 is a sectional view thereof, taken along the lines
12—12 of FIG. 5, looking in the direction of the arrows.

The stippled shading on the design indicates a contrast
such as frosting.
